CONCRETE PLACING EQUIPMENT

Mark C. De Wolfe, Oakland, Calif.

Application June 16, 1930. Serial No. 461,498

2 Claims. (Cl. 187—95)

My invention relates to improvements in concrete placing equipment, and it consists in the combinations, constructions and arrangements hereinafter described and claimed.

5 An object of my invention is to provide concrete placing equipment which comprises parts that can be formed into a tower, a boom, a machine, a gallus frame, etc., the parts being interchangeable so as to form structures varying in 10 height according to the type of work to be accomplished. Part of the equipment consists in tracks that may be extended up along the sides or interior of a tower, these tracks having a smooth exterior surface throughout their entire 15 lengths even though they are made up of a number of sections. If desired, two towers may be erected and connected together when heavy duty work is to be done.

I also provide novel means for adjusting 20 hoppers at different places on the tower and for providing trips that will cause a bucket to dump into the desired hopper. These trips or dumps may be swung into an out-of-the-way position so as to permit the bucket to move to the top of the 25 tower, as, for example, when it is desired to carry workmen to the top for inspection of the tower.

A still further object lies in the fact that the tie wires supporting the tower do not interfere 30 with the tower top, and this permits additional sections to be added so as to increase the height of the tower as desired.

Other objects and advantages will appear as 35 the specification proceeds, and the novel features of the invention will be particularly pointed out in the claims hereto annexed.

My invention is illustrated in the accompanying drawings, in which:

Figure 1 is a side elevation of the complete assembly,

40 Figure 2 is a horizontal section along the line 2—2 of Figure 1,

Figure 3 is an enlarged horizontal section of a corner of the tower,

Figure 4 is a side elevation of Figure 3,

45 Figures 5, 6 and 7 are perspective views of various parts of the equipment,

Figure 8 is a section along the line 8—8 of Figure 1,

50 Figures 9 and 10 are side and top plan views respectively of the part connecting two towers together,

Figure 11 shows another member forming a part of the tower, and

55 Figure 12 illustrates how the different sections may be secured together.

In carrying out my invention I provide a tower indicated generally at 1 and of the shape shown in Figure 1. Reference to Figure 2 shows the tower as being composed of four legs 2, these legs being made up of tubular sections 3 (see Figures 3 and 4) connected together by leg joints of the type shown in Figure 6 or of the type shown in Figure 7.

The leg joint 4 shown in Figure 6 comprises a body portion 5 having a diameter equal to the outer diameter of the sectional legs 3. Two reduced portions 6 (see Figure 6) are integral with the body portion 5, and these are receivable in the leg sections 3 as shown in Figure 4. If desired, the leg sections 3 may be provided with openings 7 (see Figure 4), and these will register with openings 8 in the reduced portions 6 for receiving bolts 9 of the type shown in Figure 12. The leg joint 4 also carries a lug 10 that extends away from the leg 2 as shown in Figure 3, and a guy wire 11 (see Figure 2) may be passed through an opening 12 (see Figure 6) in the lug 10 and extend to a supporting surface such as the ground or other object. In this way the tower is braced. It is obvious that the lugs 10 may be lengthened so as to be attachable to a supporting member such as a framework or the like. In this event the guy wires 11 could be dispensed with.

In Figure 1 I show the guy wires as being secured to every other section of the tower. I have denoted one section by the letter A in Figure 1, and as many sections as necessary may be added to the tower. Leg joints 13 (see Figure 7) are used to connect the sections not employing guy wires 11. It will be noted that the leg joint 13 is identical to the leg joint 6 except that the lug 10 is dispensed with. Corresponding parts will therefore be given like reference numerals, and a further description is not needed.

The four legs 2 are disposed in foot members 14 (see Figure 1), and these members have tubular portions for receiving the leg sections 3, and, if desired, they may have central portions (not shown) entering the leg sections 3. The legs 2 are connected to each other by channel irons 15 (see Figures 2 and 3). The ends 16 of the channel irons 15 are bent as shown in Figure 3, and a bolt 17 is passed through the openings in the ends 16 and through an opening 18 (see Figures 6 and 7) in the joints 4 or 13 so as to secure the channels 15 to the legs 2. The channels in reality are secured to the portions 5 of the joints 4 and 13. Lacing members consisting of struts 19 are disposed diagonally as shown in Figure 110

1, and these struts have bent ends that are secured to the legs 2 by the same bolts 17.

As an added means of reinforcement, I provide inner channels 20 (see Figure 2) on two sides of the tower, and these channels have ends bent so as to be secured to the legs 2 by the bolts 17. Bracing members 21 (see Figure 3) extend across the corners of the tower and are secured to the channels 15 and 20 by bolts 22 and 23.

10 The same bolts 22 and 23 are used for supporting tracks. In Figure 2 I show five sets of tracks indicated by the letters B, C, D, E and F. These tracks are formed of tubular sections 24 and may be of the same size as the leg sections 3 or of a smaller diameter. Track joints 25 of the shape shown in Figure 5 are disposed between adjacent track sections 24 and support the sections as well as hold them in alignment with each other. It will be noted in Figure 5 that the track joint 25 has a central portion 26 having the same outer diameter as the outer diameter of the track sections 24. Reduced portions 27 are used for entering the tubular track sections. It will be seen that a smooth continuous surface will extend 25 along the entire length of the tracks because of this construction. The portion 26 has a T-shaped lug 28 that is secured to the channel irons 15 by the bolts 22 and 23 (see Figure 3). Additional bracing members 29 may be provided if necessary, 30 and these extend from the lugs 28 to the bolts 17.

Various types of sliding equipment can be raised and lowered on the tracks B to F inclusive, and in Figure 1 I have shown a frame 30 35 slidably carried by the track D. A hopper 31 is carried by the frame, and a boom 32 is also carried by the frame. If desired, a counter-balance 33 may be suspended from the boom, and a gravity chute 34 may connect the hopper 31 with a chute 35 carried by the counter-balance. The 40 raising and lowering of the frame 30 on the track D will raise and lower this entire equipment.

As a further illustration, I show a second hopper 36 similar to the hopper 31 adjustably carried by a frame (not shown) which is slidably 45 on the track B. A chute 37 leads from this hopper to any place desired.

Within the tower I show a bucket hoist 38 that is guided by the track F. The particular type of bucket 39 carried by the hoist 38 is described 50 in my co-pending application on a Hoist bucket filed June 16, 1930, Serial No. 461,497. Suffice it to say that the bucket is tiltable to the right or to the left in Figure 1 with respect to the support 38, and this is accomplished by rollers 40 55 that are receivable in arcuate grooves 41 in trips 42. The trips are pivotally carried by the hopper 36 at 43 for permitting the trips to be swung into or out of operative position. The movement of the platform 38 upwardly caused by the lifting of the supporting bail 44 will cause the roller to enter the grooves 41 and to dump the contents 60 of the bucket 39 into the hopper 36. Should the operator forget to stop the platform 38 at the proper position, the platform will continue to 65 move upwardly and the rollers 40 would enter arcuate grooves 45 in the trips 42, and the bucket would continue on its upward movement in a dumping position. The return movement of the bucket would cause the rollers to again enter 70 the grooves 45 and to enter the grooves 41, whereupon the bucket will be swung into an upright position.

A similar double trip or dump may be provided for the hopper 31, none being shown. All of 75 the trips may be swung into inoperative position

about their pivots 43 when it is desired to raise the bucket 39 to the top of the tower. In Figure 8 I show a detail of the track F, the platform 38, the bucket 39, and the bail 44. This figure illustrates how shoes 46 secured to the bail 44 80 slidably engage with the track F so as to guide the bucket and at the same time not interfere with the projection 28.

When it is desired to secure two towers together so as to provide a structure which will withstand heavy duty, I provide connecting means as shown in Figures 9 and 10. The connecting means consists of two of the joints 4 secured to each other by their lugs 10. In Figure 9 I show a connecting strip 47 having cylindrical 90 end portions 48 with reduced portions 49 designed to enter the tubular members 3. Figure 10 shows a top plan view of the same structure. The two towers can support six exterior tracks and two interior tracks if desired. Tracks can also be 95 placed between the towers. In fact, a third tower is formed between the other two by this construction, and this third tower can be extended above the others to carry an elevator or bucket.

It is now the practice to suspend load lines from the top mid-portion of the tower and have these load lines support gravity chutes, counter-balances, etc. It is impossible with this construction to add to the height of the tower without first moving the load lines. In the present device I provide a joint 50 of the shape shown in Figure 11, and this joint takes the place of joints 4 or 13. The joint 50 is preferably placed at the desired height in the tower, and it carries a projection 51 normally termed a saddle support, and in this support there is disposed a half pipe or saddle 52 which in turn receives a load line 53, this load line carrying chutes etc. not shown. Preferably at least two load lines 53 are used, 115 one being disposed on each side of the tower. A new section can be added, and this will not interfere with the load lines because, as already stated, they are disposed on the sides of the tower. If it is desired to lift the load lines to the top of 120 the new section, joints 50 can be added to the top of the section and then the load lines lifted so as to be supported by the topmost joints 50.

The lacing members 19 are interchangeable, and they may be of various lengths for towers 125 of different sizes. It is obvious that the tower 1 can be used as a mast if the top and bottom of the tower are provided with conical-shaped sections so as to permit the mast to be rotatably supported at its base. It is also obvious that a boom 130 can be constructed of the tubular sections 3 and the joints 4, and that this boom may be reinforced by cables extending from the lugs 10 of the joints 4 to the ends of the boom. The boom may be made in sections, and these sections 135 secured together by the joints 4.

It will further be noted that the towers can be used for supporting railroad tracks either passed through the towers or supported at the sides of the towers. In building dam structures the towers would be erected and spaced the required distance apart. The railroad tracks would be supported by the towers, and as the concrete was poured, the towers would become embedded and form a part of the reinforcing structure for the dam. As the height of the dam increased, additional sections could be added to the towers and the railroad tracks raised as needed.

Although I have shown and described one embodiment of my invention, it is to be understood 150

that the same is susceptible of various changes, and I reserve the right to employ such changes as may come within the scope of the claims here-to annexed.

5 I claim:

1. An article of manufacture comprising two cylindrical members connected to each other by an integral cross piece, each member having two integral cylindrical end portions of less diameter than the members the end portions having smooth surfaces throughout their lengths.

10 2. A coupling for a sectional tubular track com-

prising a body having the same diameter as the outer diameter of the tubing, said body having integral cylindrical portions whose axes coincide with each other and with the body axis, the outer diameters of the cylindrical portions being the same as the inner diameter of the tubing, and a laterally extending integral supporting portion for the body having a thickness far smaller than the outer diameter of the tubing, whereby the greater portion of the tubing and body can be utilized for guiding means.
